UNITED STATES PATENT OFFICE.

SYLVESTER L. JOINER, OF McGREGOR, TEXAS.

COMBINED GRAIN-DOOR STRIP AND SIDE-DOOR-POST PROTECTOR.

Application filed March 5, 1927. Serial No. 173,125.

The invention relates to a combined grain door strip and side post protector.

The object of the present invention is to provide a simple, practical, and efficient combined grain door strip and side door post protector of strong, durable and comparatively inexpensive construction adapted to be readily applied to a box car interiorly of the same at opposite sides of the door opening and comprising a metal housing for protecting the side door post of box cars, and a wooden strip supported in the housing and protected by the same and enabling the boards of a grain door to be secured in position without the nails or other fastening devices penetrating the side door posts of the car and injuring the same.

Another object of the invention is to provide a combined grain door strip and side door post protector adapted to last as long as the car to which it is applied and capable of enabling the wooden strip which receives the fastening devices of the grain door to be removed when necessary and adapted to support the wooden strip at opposite sides of the same and thereby enabling the said strip to last for a considerable length of time before requiring removal and until it becomes necessary for the box car to be overhauled or rebuilt.

Another object of the invention is to provide a combined grain door strip and side door post protector which will serve as a shield to prevent the hand trucks which are employed for loading and unloading cars from coming in contact with and cutting, marring or otherwise injuring the wooden door post of the car, and which will present smooth rounded surfaces at the exposed corners of the metal housing for contact with hand trucks or other objects.

With these and other objects in view, the invention consists in the construction and novel combination and arrangements of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a longitudinal sectional view of a car showing a portion of one of the side

doors in elevation equipped with a combined grain door strip and side door post protector constructed in accordance with this construction.

Fig. 2 is a central longitudinal sectional view through one of the grain door strips and side door post protectors partly broken away to enable it to be shown on a larger scale.

Fig. 3 is a transverse sectional view on the line 3—3 of Fig. 2.

Fig. 4 is a transverse sectional view of the combined grain door strip and side door post protector taken at a point between the integral connecting bars and showing converging fastening devices for securing the wooden strip to the housing.

Fig. 5 is a transverse sectional view of a combined grain door strip and side door post protector equipped with a T-shaped filler strip.

Fig. 6 is a transverse sectional view illustrating a modification of the T-shaped filler strip and the housing for the same.

Referring particularly to Figs. 1 to 3, inclusive, of the drawings, the combined grain door strip and side door post protector consists of a metallic housing constructed of any suitable material and composed of spaced side bars 1 and integral transversely disposed connecting bars or back portions 2 arranged at the center and ends of the metallic housing, as clearly illustrated in Fig. 2 of the drawing, but any desired number of integral connecting cross pieces or bars 2 may, of course, be employed, as will be readily understood. The side bars may be made of any desired size and are preferably castings, and the space or longitudinal opening between the side bars receives a wood filler strip 3, which is dovetailed into the housing. The side bars 1 are undercut at an angle or beveled at their inner sides at 4. The side edges 5 of the filler strip 3 are correspondingly bevelled to fit the bevels in the side edges of the said side bars 1 and to provide tapered side portions, as clearly shown in Fig. 3 of the drawing. A transversely tapered filler strip 3 is approximately semi-hexagonal or half prism-shaped and is adapted to slide endwise into the tapered side bars of the housing.

When the housing is secured in position to the side of the door opening of a car, the filler strip will be securely retained in place. Also, the tapered filler strip is secured to the housing by means of bolts 7 which pass through the filler strip and the integral cross

bars of the housing at the centers of the said cross bars. The side bars 2 are also rounded exteriorly at 8 at the outer corners of the housing to present smooth rounded surfaces 5 to hand trucks and other objects and prevent the same from being caught by the housing. Should a hand truck strike the housing, it will readily slide off the same and will not catch on the rounded corner thereof. The 10 bolt 7 has its head countersunk in the rear face of the cross bar 2 and the nut 9 is let into the filler strip as clearly shown in Fig. 3 of the drawing, a suitable recess 10 being provided for each of the nuts 9. This will 15 arrange the outer faces of the nuts in flush relation with the outer face of the filler strip and not interfere with the arrangement of the boards of the grain door on the housing and filler strip, and at the same time 20 will prevent the nuts from turning while the bolts are being tightened after the filler strip has been placed in position and before the housing is secured to the side of the car.

Also, the dovetailed filler strip may, as 25 illustrated in Fig. 4 of the drawing, be secured in the metallic casing by inwardly converging fastening devices 11, and for this purpose the side flanges 12 of the metallic casing, the cross bar 13 and the filler strip 30 14 are provided with perforations 15 which extend through the device from the outer face of each flange to the inner face of the cross bar. The outer ends 16 of the perforations 15 are countersunk to receive the 35 heads of the fastening devices which are arranged in flush relation with the adjacent faces of the side flanges. Any suitable form of fastening devices may be employed and the fastening devices may extend beyond the 40 metallic housing for securing the same to the car. The fastening devices are designed to be arranged at any suitable intervals along the side bars both at the points where the transverse connecting bars occur and also at 45 intermediate points.

In Fig. 5 of the drawings is illustrated another modification of the invention, in which a filler strip 17 approximately T-shaped in cross section is employed. The T-shaped 50 cross section is interlocked with the metallic housing 18 and has laterally extending side flanges 19, and presents flat faces to the inner faces of the metallic housing. The side bars 20 of the metallic housing are grooved at 55 to receive and conform to the configuration of the laterally extending flanges of the filler strip. The filler strip is secured in the metallic housing by suitable fastening devices 22 arranged in perforations 23 disposed in parallelism and extending through the overhanging portions of the side bars and through the flanges of the filler strip and through the transverse connecting bars of the housing, as clearly shown in Fig. 5 of the drawings. The outer ends 24 of the perforations

23 are countersunk to receive the heads of the fastening devices, which may be of any desired form. The filler strip 17 has a reduced portion 25 formed by recessing it to provide the laterally extending flanges, and 70 the reduced portion fits within the side bars 20 and is arranged in flush relation with the same, as clearly illustrated in Fig. 5 of the drawing.

In Fig. 6 of the drawing is illustrated a 75 modification of the T-shaped filler strip. In this form of the invention the filler strip 26 is provided with laterally extending flanges 27 of increased size and a relatively narrow portion 28 is arranged between the side bars 29 of the metallic housing 30. The side bars are curved in cross section as shown, and the side flanges 27 of the filler strip are rounded to present curved faces to the inner faces of the side bars of the metallic housing. In the form of the invention shown in Fig. 5 the fastening devices 22 are arranged parallel, while in the present form of the invention converging fastening devices 31 are employed. The 80 fastening devices 31 are arranged in converging perforations 32, which extend through the curved side bars 29, the laterally extending flanges 27 of the filler strip, and the cross bars 33 of the metallic casing. 85

What I claim is:

1. A combined grain door strip and side door post protector located interiorly of a car at opposite sides of the door opening thereof and comprising a metallic housing composed of spaced longitudinal side bars consisting of angularly disposed flanges provided with smooth exteriorly curved contact faces and having their inner side edges undercut, and connected together at their back edges by spaced cross pieces, a wood filler strip arranged in the metallic housing and having laterally projecting side portions fitting the undercut side edges of the said side bars, said filler strip being provided with a reduced front portion arranged between the side bars in flush relation with the outer faces thereof, said filler strip filling the space between the side bars of the housing, said filler strip being adapted to receive the fastening device of a grain door, and devices piercing the wood filler strips and the aforesaid back cross pieces whereby to secure the strip and housing together. 100

2. A combined grain door strip and side door post protector located interiorly of the car at opposite sides of the door opening and comprising a metallic housing including spaced longitudinal side bars consisting of angularly disposed flanges provided with smooth exteriorly curved contact faces and having their inner side edges undercut to provide a tapering intervening space between the side bars, and a wood filler strip beveled at its side edges to provide tapering portions to fit the undercut edges and the tapered in- 110 115 120 125 130

tervening space between the side bars, said 5 filler strip filling the space between the side bars and having a narrow portion located at the outer faces of the side bars and in flush relation with the same, the filler strip being adapted to receive the fastening devices of a grain door, and devices piercing the front portions and also back portions of the housing and the wood filler strip to secure same 10 together.

3. A combined grain door strip and side door post protector located interiorly of the car at opposite sides of the door opening and comprising a metallic housing including 15 spaced longitudinal side bars consisting of angularly disposed flanges provided with smooth exteriorly curved contact faces and having their inner side edges undercut to provide a tapering intervening space between the 20 side bars, and a wood filler strip beveled at its side edges to provide tapering portions to fit the undercut edges and the tapered intervening space between the side bars, said filler strip filling the space between the side bars 25 and having a narrow portion located at the outer faces of the side bars and in flush relation with the same, the filler strip being adapted to receive the fastening devices of a

grain door, said combined grain door strip and side post protector being provided at 30 intervals with converging perforations extending through the side bars and through the tapered portions of the filler strip and back portions of the housing, and devices fitted in said converging perforations to secure the housing and strip together. 35

4. A combined grain door strip and side door post protector located interiorly of the car at opposite sides of the door opening and including a wooden filler strip, a metal back 40 fitted against the car and to which the filler strip is secured, and a metal side flange arranged at an angle to the metal back at the door opening of the car and curved transversely and presenting a smooth exterior convex contact face and overlying the adjacent portion of the filler strip and presenting a smooth concave inner face to the filler strip, the latter being recessed to receive the said flange and presenting a transversely curved 45 convex face to fit the said flange, the flange and filler strip being arranged in flush relation at the front. 50

In testimony whereof I have hereunto set my hand.

SYLVESTER L. JOINER.
